UNITED STATES PATENT OFFICE

123,887

DESIGN FOR A DIFFUSER-PROJECTOR FOR LIGHTING FIXTURES

Charles H. Koehler, Chicago, Ill.

Application March 29, 1940, Serial No. 91,336

Term of patent 14 years

To all whom it may concern:

Be it known that I, Charles H. Koehler, a citizen of the United States, residing at Chicago, in the county of Cook and State of Illinois, have invented a new, original, and ornamental Design for Diffuser-Projector for Lighting Fixtures, of which the following is a specification, reference being had to the accompanying drawing, forming part thereof.

Fig. 1 is a perspective view of the diffuser-

projector viewed from above, showing my new design.

Fig. 2 is a perspective view thereof viewed from below. The dominant features of my design reside in the portions shown in full lines.

I claim:

The ornamental design for a diffuser-projector for lighting fixtures, substantially as shown and described.

CHARLES H. KOEHLER.
